UNITED STATES PATENT OFFICE.

JOHN C. SAGE, OF ATLANTA, GEORGIA.

GRADING AND DITCHING MACHINE.

SPECIFICATION forming part of Letters Patent No. 378,406, dated February 21, 1883.

Application filed July 2, 1887. Serial No. 243,291. (No model.)

To all whom it may concern:

Be it known that I, JOHN C. SAGE, a citizen of the United States, residing at Atlanta, in the county of Fulton and State of Georgia, 5 have invented certain new and useful Improvements in Grading and Ditching Machines, of which the following is a specification.

My invention consists in the improved construction, arrangement, and combination of 10 parts of a grading and ditching machine, as will be hereinafter fully described, and pointed out in the claims.

Referring to the accompanying drawings, Figure 1 is a side view of my improved grading and ditching machine, showing the power-wheels in dotted lines. Fig. 2 is a plan view of the same, partly in section. Fig. 3 is a rear elevation. Fig. 4 is a detail side view of the main conveyer with the power-wheels 20 applied. Fig. 5 is a detail cross-section on line 5 5, Fig. 4. Fig. 6 is a partial front view of the machine. Fig. 7 is a top plan showing the plows and main conveyer shifted to one side of the machine. Fig. 8 is a detail front view 25 of the plow-beam with plow-frame and plows. Figs. 9, 10 are detail views, hereinafter referred to; and Fig. 11 is a detail cross section on line x x, Fig. 1.

The same letters of reference indicate corresponding parts in all the figures.

In the accompanying drawings, A A represent the main frame, which is suitably mounted on the axles a a', said axles having the drive-wheels B B. C denotes the plow-beam, 35 to the lower end of which is secured the plow-frame D.

By reference to Fig. 8 it will be seen that the plow-frame consists of the cross-beam d, having the vertical side beams, d'. Secured to 40 each of the side beams are the plows E E', and to the cross-beam d is secured the shovel or colter plow F. The plow-beam C is loosely connected to the main frame.

The main conveyer G is connected at its forward end to a cross bar, e, and windlass H' by the cable 1, and at its rear end it is movably connected to the cross-bars f of the main frame in the following manner: The center bar or axle, I, passes through the drum or belt pulley i, and 45 has its ends projecting at either side thereof, as shown in Fig. 11. The body portion 1 of the axle I is square in cross-section, while the

ends 2 thereof are round, to form spindles or bearings to run in the boxes 3. These boxes are arranged to slide in the grooves 4 in the 55 cross-timbers f.

The drum or pulley i is made with a square hole through its center and a little larger than the center axle, I, the object of this being to allow the drum to be moved to either side as 60 much as possible. When the plows are working on the side of the machine, the drum is held in position on the center bar or axle, I, by the clamps 5. These clamps also secure to the axle I the belt-pulleys 6 6, which will be here- 65 inafter referred to.

Secured to the top of the main frame and arranged transversely thereto are cross-beams J J'. Fitting over the timber J is a movable iron loop-hook, j, to which is fastened the end 70 of a cable, 7. From this hook the cable 7 passes over a pulley, 8, secured to the center of the plow-frame D, and thence over a pulley, 9, secured to cross-piece J', to the windlass H. By this arrangement it will be seen that, should 75 the plow be working on one side of the machine and it be desired to move it to the other side, it will only be necessary to allow the plow to rest on the ground and move the loop-hook j on the cross-beam J to the other side of 80 the machine. Then by tightening the windlass H the plows will be raised, and they can then be placed at any point desired. The front end of the main conveyer is arranged in a similar manner. The cable or chain 1 is connected to 85 the loop-hook 2, which slides on the cross-bar C, passes over a pulley, 10, connected to the main conveyer-frame, and thence over the pulley h to the windlass H'.

To each of the plows E is secured a clevis, 90 K, to which hooks the center drag-chain, L, and the outside drag or stay chains, L'. On each end of the center drag-chain, L, is arranged hooks 11 12. One of these hooks, 11, is hooked into the clevis at any desired point. 95 The other end of the chain passes through a ring, 13, in the back end of an iron "dog-bar," 14, thence back and hooked into one of its own links. The iron dog-bar is shown in detail in Figs. 9 and 10, and consists of a flat 100 piece of iron, its upper end looped so as to allow the pole or tongue M to pass through it, said looped part being provided with a spur, 15, which enters into notches in wear-

plate N on the upper face of the tongue M, thus forming a hinge-bearing.

Near the back end of the dog-bar is a series of small holes, 16, into any one of which and 5 through a hole, 17, in the tongue or pole the lock-pin 18 can enter. The object of this arrangement is to control the line of draft, and by arranging the spur 15 and lock-pin 18 in the proper holes the horses will be relieved 10 from any unnecessary weight from the pole or tongue. The outside drag or stay chains are arranged thus: One end is wrapped around the front axle and hooked into one of its own links and the other end hooked to the clevis K. 15 Generally only one outside chain would be used. When the machine is to be turned around, it would be necessary first to release the outside chains and with the windlass raise the plow up out of the way, and as the front 20 wheels are low enough to turn under the floor A² of the machine the same could be turned in a space very little more than its own length.

A² represents the floor of the machine, and is divided into two parts, the rear part extending 25 from the back end of the machine to a little in front of the hind axle, the front part from a point about over the plow-points to the front end of the machine, as shown.

When the machine is to be moved any considerable 30 distance, the plows and main conveyer may be raised up so as to admit of a false floor being placed under them, and thus relieve the windlass and at the same time have the load as close to the ground as possible.

35 M represents the pole or tongue, which is connected to the main frame of the machine by the king-bolt m. This pole can be shifted laterally by removing the king-bolt m and adjusting same in a series of holes in the front axle and beam A³ of the main frame. Brace-chain O, which is fastened at each end to the axle near the hubs, passes through an aperture, 20, in the pole, and can be secured at any 40 desired point by a suitable lock-pin, 21.

The plows E E are placed in the center of the plow-frame, which leaves room enough to allow the plows to work as far out as possible on each side and at the same time run level 50 and allow the plow-beam to pass under frame-timber A'. To the cross-piece d of the plow-frame, and extending rearwardly, is secured an apron or shield, 30, to guide the earth onto the main conveyer.

55 Motion is imparted to the main conveyer as follows: 21' represents a pulley or drive shaft, a, from which runs a crossed cable, a⁵, up over a pulley, 22, on a shaft, 23. On this shaft are mounted pulleys 24 24, from which the endless cables 25 25 run over the pulleys 6 6 on the upper shaft, I, of the main conveyer. The pulleys 24 24 are movable and are arranged in this manner, so that they can be shifted when the main conveyer-drum is moved to either side.

60 65 If at any time it becomes necessary to have more power than the two drive-wheels produce (as in case of the earth being wet or of

such a nature as to let the drive-wheels slip) to run the main conveyer, power-wheels P P may be applied to the lower end of the conveyer as follows:

70 Journalized in the center timbers of the main conveyer, transversely thereto and at the lower end thereof, is a short shaft, 27, the ends of which are threaded and are so cut that when 75 the power-wheels P P are turned they will tighten up until the backs of the wheels jam up hard against the washers 28 28, which in turn bear hard up against the center timbers of the conveyer G.

80 The power-wheels P are so constructed that their spokes p, which are of iron or iron-pointed, go through the tire, so as to enable them to take better hold on the earth. The power-wheels are provided with grooved pulleys 29, from which runs a crossed cable or belt, 60, to the pulleys 6 6, as shown.

Fig. 7 shows the plows working to one side, the object of this being to enable the plow to remove the earth close up to the side of a cut 90 when said side is to be left perpendicular, or nearly so. When the plow is in this position, the upper end of the conveyer G is in a slight crosswise position, as shown. This, however, does not interfere with the working of the machine. R represents the auxiliary or side conveyer, which is supported between the vertical beams 31 31 of the main framing of the machine and arranged transversely to the main conveyer. This conveyer R is adapted 95 to receive the earth from the main conveyer and deposit the same either into a wagon or to either side of the machine.

100 32 32 are the side timbers of the conveyer R, in each end of which are journalized the 105 drums or pulleys 33 33, over which passes the endless conveyer-belt. As will be seen by reference to Fig. 3 of the drawings, this conveyer is adjustably secured to the main frame of the machine as follows:

110 34 34 represent the spindles of the drums 33 33, said spindles extending a short distance beyond the side timbers of the conveyer, as shown. These spindles have their bearings in the Ω -shaped bails 35 36, to the upper central 115 portions of which is connected the supporting-chain 37. This chain passes over the pulleys 38 38, suspended from the top cross-piece, 39, of the main frame.

120 By suspending the conveyer R in the manner described it may readily be placed in any desired position, and when in such position it can be securely held in such position by means of the pins 40 40, which pass through one of a series of holes, 31^x, in the timbers 31 31, and 125 any one of the holes 41 41 in the side timbers of the conveyer R. This conveyer receives motion from the shaft by means of an endless chain or belt, 42, which passes over pulley 44 on the shaft 23, thence over loose pulleys 45 45, secured to the main frame, thence over loose pulleys 46 46 on the side timber of the conveyer, and thence over the pulleys 47 48 on the spindles 34 34, as shown. When it is de-

sired to change the conveyer R from one side to the other, remove the pins 40 40, then by hand push the conveyer to the desired position, repin it, and change or cross the cable 42.

5 To operate the machine, it would be first necessary to get it headed in line of the excavation. Then, with plow and main conveyer in position, the machine is moved forward, the plows E will sink into the earth as deep as allowed by the windlass H, the earth as cut by the plows will be forced upon the apron 30 onto the main conveyer G, from which it drops onto conveyer R, and thence deposited on either side into wagons or carts, or, if digging a 15 ditch, dropped on the ground on either side desired.

While I have described my machine as being arranged to be operated by horse-power, it is manifest that the same could be operated 20 by traction-engine power. In this case it would only be necessary to disconnect the pole or tongue and attach the front axle of the machine to the engine by chains or any other suitable manner; or the front wheels could be 25 taken off, and the front end of the frame can be fastened to the back end of the engine and plows fastened to the axle of the drive-wheels.

Having thus described my invention, what I desire to claim and secure by Letters Patent 30 is—

1. In a grading and ditching machine, the combination, with a main frame or platform, A, carrying plows E, of the main conveyer G, disposed to receive the earth from the plows, 35 said conveyer adjustably connected to the main frame A, and provided at its lower end with the power-wheels P P, (said wheels having the drive-pulley 29,) and the pulleys 6 6, at its upper end, adapted to impart motion to 40 the conveyer through the chain or belt 60, substantially as shown.

2. In a grading and ditching machine, the main conveyer G, said conveyer being adjustably secured at its lower end to the main 45 frame A by means of the cross-piece e, chain or cable 1, pulleys 10 h, and windlass H', and movably secured to the main frame at its upper end, substantially as shown.

3. In a grading and ditching machine, the 50 main conveyer G, adjustably secured at its lower end to the main frame A and movably secured at its upper end to the main frame, said conveyer having the shaft I, carrying the drum i, said shaft journaled in sliding boxes 55 3, said boxes adapted to slide in grooves in the cross-piece f, substantially as shown.

4. In a grading and ditching machine, the main conveyer G, adjustably connected at its lower end to the main frame and provided at its upper end with the shaft I, said shaft provided with the drum or belt pulley i, the body portion of said shaft being square in cross-section, said shaft provided with the drive-pulleys 6 6, and securing-clamp 5 5, the ends of said shaft being round, adapted to journal 60 65 in sliding boxes 3, said boxes adapted to slide in the grooves 4, substantially as shown.

5. In a grading and ditching machine, the combination, with the main conveyer, of the auxiliary conveyer R, said conveyer being 70 adjustably suspended transversely to the main conveyer on the main frame and adapted to a movable adjustment by means of the lock-pins 40, and holes 31^x and 41, substantially as shown.

6. In a grading and ditching machine, the combination of the main frame of the beam C, having the plow-frame D, said frame having the plows E E and colter F and apron 30, secured thereto, the clevis K and draft-chains 80 L L', secured to the dog-bar 14, said beam and plows adapted to vertical and lateral adjustment by means of the cross-bar J, cable 7, pulleys 8 and 9, and windlass H, substantially as shown.

7. In a grading and ditching machine, the combination of the plow-frame D, having the plows, said frame provided with the drag-chain L of the dog-bar 14, said bar connected with the drag-chain, substantially as shown.

8. In a grading and ditching machine, the combination of pole M, having notches in its upper face, of the dog-bar, said bar adapted to embrace the pole, and provided with the spur to enter the notches in the pole, and provided with the rearwardly-extending arm, said arm having holes to receive the lock-pin 18, and provided with the ring 13, adapted to receive the end of drag-chain, substantially as shown.

9. In a grading and ditching machine, the main conveyer G, provided with a transverse shaft at its lower end, the said shaft having a screw-threaded journal adapted to receive the power-wheels P, the spokes of said wheels 105 passing through the tire, substantially as shown.

JOHN C. SAGE.
